H. E. LONG

By Marked Clark Attn's

UNITED STATES PATENT OFFICE.

HARRY ERNEST LONG, OF WELLINGTON, NEW ZEALAND.

LIFE BUOY.

Application filed July 24, 1922. Serial No. 577,203.

To all whom it may concern:

Be it known that I, HARRY ERNEST LONG, a subject of the King of Great Britain and Ireland, residing in Wellington, New Zealand, have invented a new and useful Improvement in Life Buoys; and I do hereby declare the following to be a full, clear, and exact description of the same.

This invention relates to life-buoys of the usual circular form.

The object of the invention is to provide a buoy of great buoyancy, which will be rigidly constructed and in which the maximum strength, lightness, and utility for life-saving purposes is obtained.

According to this invention the buoy is constructed of a strong cane frame divided into one or more water-tight compartments, stuffed with kapok and covered with a specially prepared canvas or other suitable covering. Over these compartments another layer of kapok is employed covered with water-proof canvas. If desired, ropes may be attached around the buoy.

The invention will be illustrated in the accompanying drawings, wherein:

Figure 1, is a plan of the finished buoy.

Figure 2, is a plan of the frame-work.

Figure 3, is a cross section through the buoy.

Figure 4, is a cross section through a portion of the buoy drawn to a larger scale than any of the preceding views.

Figure 5, is a plan showing a mode of reinforcement.

Figure 6, is a perspective view of a detail.

Referring now to the drawings, the buoy consists of a ring 1 of cane, and an outer ring 2 also of cane. Such rings are held in position by cork or wooden braces 3 (see Figure 6) having their inner and outer edges curved as shown, while the rings 1 and 2 are secured to such braces by nails 4. Between the inner and outer rings layers of canvas 5 and 6, cut in a circular shape, are secured by stitching 7 upon the inner sides of the rings 1 and 2. This compartment formed by the layers 5 and 6 is stuffed with kapok 8 and the upper layer stitched down as the stuffing proceeds, thus forming a casing for the kapok. Other layers of canvas 9 and 10 are similarly cut and secured around the rings 1 and 2 upon the outer side of such rings

and stuffed with kapok 11, the edges of the layers 9 and 10 being stitched together at 13, 55 thus forming an outer water-proof casing.

After the inner casing is sewn up the buoy is dipped into a water-proofing solution, and after the outer casing is sewn the buoy is again dipped into the same solution, which 60 renders both the inner and outer casing water-proof so that should the outer casing become, in any way damaged or perforated, and the stuffing below such outer casing become water clogged, the buoy will still float, 65 since the main portion of the stuffing would be protected by the water-proofed inner casing.

To water proof the inner and outer casing the buoy is simply dipped into the solution 70 and allowed to dry.

In Figure 5, the inner and outer rings 1 and 2 are reinforced by bracing 14 formed of cane bent in the form shown and zigzagging from one ring to the other and secured 75 to the rings by lashing 15.

What I claim is:

1. In a life buoy of circular form having water-proof compartments, a frame consisting of an inner ring, an outer ring, braces supporting said rings, an inner casing of water proof material attached upon the inner edges of such rings, said casing stuffed with a buoyant material, an outer casing of 80 water proof material around the exterior of the rings, the space between the said inner casing and such outer casing stuffed with a buoyant material, substantially as described.

2. In a life buoy of circular form having water-tight compartments, an inner ring of cane, an outer ring of cane, braces of wood at intervals between the said rings, said rings being secured to said braces, a casing of water-proof canvas sewn to the inner sides of said rings, said inner casing stuffed 90 with kapok, an outer casing of water-proof canvas secured upon the exterior of the rings, the space between said inner casing and said outer casing stuffed with kapok, 95 substantially as described.

3. In a life buoy of circular form having water-tight compartments, an inner ring and an outer ring, braces supporting said rings, an inner casing and an outer casing of water-proof canvas attached to the inner 105 and outer sides of said rings, said inner cas-

ing stuffed with kapok, and the space between said inner casing and said outer casing stuffed with kapok, substantially as described.

5. 4. In a life buoy of circular form having water-tight compartments, an inner ring, an outer ring, said rings braced together by zig-zag braces formed of cane, an inner casing around said rings stuffed with buoyant ma-

terial, and an outer casing stuffed with buoyant material, substantially as described. 16

In testimony whereof, I have signed my name to this specification in the presence of two subscribing witnesses.

HARRY ERNEST LONG
